UNITED STATES PATENT OFFICE

2,446,370

SAFETY ATTACHMENT FOR SHOES

Wesley Blake Henderson, Lewistown, Ill.

Application November 14, 1946, Serial No. 709,807

1 Claim. (Cl. 36—7.7)

1

This invention relates to new and useful improvements in safety attachments for shoes and more particularly to a coarse pad that is tied onto the bottom surface of the sole portion of a shoe.

Another important feature of this invention is to provide a device of the class specified that can be conveniently carried in a pocket when not in use.

A further feature of this invention is to provide a device of this character that can readily be attached to any size shoe, and one that will not scratch or mar floors when being worn.

A further important feature is to provide a safety attachment for shoes made of various colors that will in no way detract from the appearance of the wearer's shoes.

A still further important feature is to provide a device of the character referred to that is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming a part hereof, wherein like numerals refer to like parts throughout, and in which:

Figure 1 is a perspective view of the invention showing how the device is attached to a shoe.

Figure 2 is a perspective view of the invention showing the gripping surface in its attached position, and

Figure 3 is a sectional view taken on a line 2—2 of Figure 2.

Referring now to the drawings in detail, wherein, for the purpose of illustration, I have disclosed a preferred embodiment of the invention, the numeral 5 represents a flat substantially rectangular pad of preferably screen wire or a mesh wire of slightly coarser dimensions.

The forward portion of pad 5 is secured to the lower portion of an elastic toe encircling band 6 by staples 7 or the like.

To the rear portion of pad 5 that extends to the instep 5a of the shoe is attached by knots 8 or any other suitable means, a shoe string or the like 9, said string being tied tightly against the upper portion 10 of a conventional shoe 11 over the instep of the wearer.

2

To attach this device onto a shoe the wearer merely slips the toe of his shoe into toe encircling band 6 so that pad 5 rests against the bottom of his shoe. The wearer then brings the shoe string 9 over the sides of his shoe to the upper portion of the instep where he conveniently ties a bow holding the device securely to his shoe.

The device being attached affords a gripping surface to the bottom of the shoe and allows the wearer to maintain his balance on a slippery surface.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

25 What I claim:

A safety attachment for shoes comprising a flat relatively inflexible mesh wire pad, an elastic toe encircling band carried by the forward portion of said pad, said toe encircling band being positionally and dimensionally adapted for resiliently holding said pad against the bottom of a shoe sole, and a pair of strings each terminally secured to a rear outside edge of the pad, the other ends of the strings being releasably tied over the instep.
